UNITED STATES PATENT OFFICE.

HAROLD G. WARR, OF PARK RIDGE, ILLINOIS, ASSIGNOR TO THE P. & M. COMPANY, OF CHICAGO, ILLINOIS, A CORPORATION OF ILLINOIS.

RAIL-ANCHOR.

1,368,980.

Specification of Letters Patent. Patented Feb. 15, 1921.

Application filed April 9, 1920. Serial No. 372,486.

To all whom it may concern:

Be it known that I, HAROLD G. WARR, a citizen of the United States, residing at Park Ridge, in the county of Cook and State of Illinois, have invented certain new and useful Improvements in Rail-Anchors, of which the following is a specification.

My invention relates to devices for preventing the longitudinal creeping movement of railroad rails, devices of this class being commonly called anticreepers, rail stays or rail anchors.

The principal object of this invention is to improve upon the type of rail anchor disclosed in the patent to D. F. and D. L. Vaughn, No. 1,021,387, granted March 26, 1912. This type of anchor consists of a shoe member adapted to bear against a tie and to engage one edge of the base of the rail to which the device is applied, and a torsional spring yoke which extends under the rail base, engages the shoe and the opposite edge of the rail base, and is strained, when in its operative position. The present invention improves upon this type of anchor by providing a shoe member which may be more conveniently and economically manufactured than the malleable casting which forms the shoe member of the patented anchor, and one which can be made considerably lighter than the shoe of the patent, without the sacrificing of the necessary strength and rigidity required in devices of this character. The minimizing of weight in devices of this class is an important consideration, as rail anchors are manufactured in large quantities, sold at a relatively low rate per article, and frequently have to be shipped to points remote from the place of manufacture, so that the cost of transportation is a substantial factor in the cost of the articles to the railroad company.

The invention consists in the novel arrangements, constructions, and combination of parts, hereinafter described and claimed for carrying out the above stated objects, and such other objects as may appear from the following description.

The invention is illustrated in the accompanying drawings, wherein—

Figure 1 is a plan view of a rail anchor constructed in accordance with my invention, and shown applied to a rail;

Fig. 2 is a side elevation of the parts shown in Fig. 1;

Fig. 3 is a plan or upper edge view of the spring yoke member of the anchor before being applied to the rail;

Fig. 4 is a sectional elevation on line 4—4 of Fig. 1;

Fig. 5 is a diagram showing the blank from which the shoe member is manufactured, the blank being cut but not bent, the dotted lines indicating the line of bending;

Fig. 6 is a view, in perspective, of the shoe member ready for application to the rail;

Fig. 7 is a plan view of a rail showing a modified form of rail anchor;

Fig. 8 is a view in perspective of the shoe member of the device shown in Fig. 7; and

Fig. 9 is a view illustrating the form of blanks from which shoe members of the above type are formed.

Like characters of reference designate like parts in the several figures of the drawings.

Referring to the drawings, 25 indicates a railroad rail, and 26 one of the cross ties on which the rail is supported. The rail anchor, as illustrated in the drawings, consists of a shoe 27 and a spring yoke 28. The yoke is the usual form of spring yoke now used in connection with the Vaughn anchor patented in the patent above referred to. It is made from a flat piece of steel which is given a torsional set and is formed at one end with a notch 29 to engage one edge of the rail base and at the other with an upstanding lug 30 to engage the shoe member 27, the lip 31 by which the upper edge of the notch 29 is defined being bent forwardly toward the tie (having reference to the position of application of the anchor to the rail) as shown in Fig. 1.

The shoe is formed of sheet metal which is cut from a blank having the contour indicated in Fig. 5. The blank, after being cut to this shape, is bent along the lines *a*, *b*, *c*, to provide a rail base engaging jaw formed of an upper lip 32 and a lower lip 33, the latter of which preferably lies horizontally under the rail base, a tie abutting flange 34, and a connecting web 35. The blank is cut so that a notch 36 is provided between the rear edge 37 of the connecting web 35 and the forward edge 38 of the lip 33. This notch is designed to receive the lug end of the spring yoke and is preferably slightly wider than the thickness of the material from which the spring yoke is formed. The lower edge of the spring yoke is thinned

down to provide a shoulder 39. This shoulder engages a projection 40 which is formed on the edge 37 of the connecting web 35. Preferably the portion of the anchor designated 41, which connects the upper lip 32 and the lower lip 33, and the connecting web 35, is pressed out to form a boss 42. The purpose of this is to increase the width of the shoe at this place so that shoes so formed may be used interchangeably with the malleable iron shoe, heretofore employed in anchors of this type, without change of the dimensions of the spring yokes.

To apply the device to the rail, the shoe member is fitted over one edge of the rail base with its tie-abutting flange bearing against the tie. The yoke member is hooked over the other edge of the rail base, and is bent, so as to straighten out its torsional set sufficiently to permit the end of the yoke having lug 30 to be raised into notch 36 in the shoe, with shoulder 39 on the yoke engaging projection 40 on the shoe, and the upper edge of that portion of the spring yoke which extends under the rail base in interlocking engagement with the shoe member and bearing against the forward edge 38 of the lip 33. The width of the notch 36 is preferably just sufficient to permit the upper edge of the yoke member to be readily inserted to its interlocking position with clearance sufficient to permit the yoke member to assume a diagonal position across the rail base. The torsional strain to which the spring yoke is subjected keeps the anchor in close engagement with the rail. The yoke is prevented from becoming disengaged from the shoe because of the bearing of the shoulder 39 on the lug 40 and the engagement of the upper edge of the yoke with the forward edge 38 of the lip 33.

In Figs. 7 to 9 inclusive I have shown a modified form of anchor in which the lower lip 33^a of the shoe member 27^a is tapered toward its end as indicated at 41^a so as to permit the jaw end 29^a of the spring yoke 28^a to move rearwardly with the rail a greater distance than is possible with the form of lip shown in Figs. 1 to 6, inclusive, without danger of distorting or breaking the yoke. When the yoke 28^a assumes the diagonal position across the rail as indicated at "A" in Fig. 7 of the drawings, for example, during a retrograde movement of the rail when the shoe member is frozen in the ballast of the road bed or otherwise held in a relatively fixed position, the anchor device increases its grip on the rail base so as to resist further rearward movement of the rail.

The shoe member 27^a is preferably made from a blank 42 having a configuration which permits one blank to nest with another as indicated in Fig. 9. A plurality

of blanks of this form, it will be noted, may be cut from one sheet of metal without any appreciable loss of material. In other respects, the spring yoke and shoe member of the above modification may be the same as that shown and described in connection with Figs. 1 to 6 inclusive of the drawings.

This application is a continuation in part of my co-pending application, Serial No. 306,342, filed June 24, 1919.

75

I claim:

1. A rail anchor of the type described, comprising a spring yoke, and a shoe member, the latter made of a sheet metal blank, the top of which is bent on a horizontal line to form a lip to bear upon the upper surface of the base of the rail, one edge of which is bent on a vertical line to provide a tie abutting flange, the other end of which is bent on a horizontal line to form a lip to extend under the rail base, and the blank being formed so that a notch is provided defined on one side by the edge of said last named lip for engaging said yoke to hold the same under torsional strains.

2. A rail anchor of the type described, comprising a shoe member made of a sheet metal blank bent on parallel lines to provide lips which fit over the upper and lower surfaces respectively of one edge of the base flange of a rail, and a yoke member adapted to engage the opposite edge of the rail base and having an interlocking engagement with the shoe member.

3. A rail anchor of the type described, comprising a shoe member made of a sheet metal blank bent on parallel lines to provide lips which fit over the upper and lower surfaces respectively of one edge of the base flange of a rail and formed with a recess and a yoke member adapted to engage the opposite edge of the rail base and having an interlocking engagement with said recess.

4. A rail anchor of the type described, comprising a shoe member made of a sheet metal blank bent on parallel lines to provide a jaw which fits over one edge of the base flange of a rail and formed with a recess and with an outpressed boss adjacent said recess and a yoke member formed at one end with a jaw adapted to engage the opposite edge of the rail base and formed at the other end with an enlargement adapted to fit over said outpressed boss, the portion of said yoke adjacent said enlargement having an interlocking engagement with said recess.

5. A rail anchor of the type described, comprising a shoe member made of a sheet metal blank bent on a horizontal line to provide a jaw which fits over one edge of a rail base and bent on a vertical line to provide a tie abutting foot, and a spring yoke member adapted to engage the opposite edge of said rail base and be strained into an in-

terlocking engagement with said shoe member.

6. A rail anchor of the type described, comprising a shoe member made of a sheet metal blank bent on parallel lines to provide a jaw which fits over one edge of the base flange of a rail and formed with a notch provided with a rearwardly projecting lug, and a spring yoke member engaging the opposite edge of the rail base and adapted to be strained into interlocking engagement with said projecting lug and the walls of said notch.
7. A rail anchor of the type described, comprising a yoke member, and a shoe member which together engage opposite edges of a rail base and have an interlocking engagement with each other; the said shoe member being made of a sheet metal blank bent on parallel lines to provide a lip which

engages the upper surface of the rail and a lip which extends under the rail base, the latter of which decreases in width toward its end.

8. A rail anchor of the type described, comprising a yoke member, and a shoe member which together engage opposite edges of a rail base and have an interlocking engagement with each other; the said shoe member being made of a sheet metal blank having a configuration along one edge adapted to nest with the opposite edge of a correspondingly formed blank and is bent on parallel lines to provide a lip which engages the upper surface of the rail and a lip which extends under the rail base, the latter of which decreases in width toward its end to provide a clearance for said yoke.

HAROLD G. WARR.
